UNITED STATES PATENT OFFICE.

EMIL GROSS, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

NOZZLE.

Application filed September 24, 1926. Serial No. 137,458.

This invention relates in general to improvements in the construction and operation of nozzles for delivering fluid jets; and relates more specifically to improvements in the type of nozzle wherein the characteristics of the jet may be varied by relative adjustment of a control needle and the nozzle discharge orifice.

An object of the invention is to provide improved mechanism for effectively converting fluid under pressure into a jet having variable characteristics. Another object of the invention is to provide a needle controlled nozzle of relatively simple, compact and inexpensive construction, in which objectionable disturbances to the flow through the nozzle are reduced to a minimum. These and other objects and advantages of the invention will be apparent from the following description.

A clear conception of several embodiments of the invention and of the mode of manipulating nozzles constructed in accordance therewith, may be had by referring to the drawing accompanying and forming a part of this specification in which like reference characters designate the same or similar parts in the various views.

Fig. 1 is a sectional view of an impulse turbine having one form of improved hydraulic nozzle associated therewith.

Fig. 2 is a central horizontal section through a modified form of hydraulic nozzle embodying the invention.

Fig. 3 is a transverse vertical section through the nozzle disclosed in Fig. 2, the section being taken directly adjacent to the movable needle supporting and adjusting structure of the nozzle.

Fig. 4 is a side elevation of the nozzle disclosed in Figs. 2 and 3.

Fig. 5 is a transverse vertical section through the nozzle of Figs. 2, 3 and 4, the section being taken through the pipe line adjacent to the needle adjusting arms.

Fig. 6 is a central horizontal section through still another form of nozzle embodying the invention.

Referring specifically to Fig. 1, the hydraulic installation therein disclosed comprises a turbine rotor 2 rotatably supported upon a horizontal main shaft and having an annular series of buckets 3 associated with the periphery thereof; and a stationary nozzle 4 for directing a jet 7 of water against the

buckets 3 in a well known manner. The nozzle of Fig. 1 consists of a fixed pipe line or casing 4 forming a rectilinear conduit the end of which is provided with a detachable closure cap 8. The cap 8 is provided with a removable orifice ring 6 which forms an orifice concentric with the casing 4 through which the jet 7 is adapted to issue. Disposed within the casing 4 and the cap 8 directly adjacent to the nozzle ring 6, is a needle 5 which simulates a torpedo in shape, and which is movable coaxially relative to the casing 4 and the nozzle ring 6 in order to vary the characteristics of the jet 7. The needle 5 is adjustably sustained within the casing 4 by means of supports 9 which extend laterally away from the needle 5 and through openings or slots formed in the opposite side walls of the casing 4. The supports 9 are relatively thin measured transversely of the direction of flow of the water through the casing 4, and are exposed directly to the flow in order to produce minimum obstruction. The portions of the supports 9 directly adjacent to the wall of the casing 4 are provided with laterally extending flanges 14, as shown in Fig. 2, for the purpose of maintaining the guide slots in the casing 4 closed for all positions of adjustment of the needle. The casing 4 is provided with recesses or chambers 13 into which the lugs 26 extend, and the lugs 26 coact with renewable guideways 24 secured within the guide openings of the casing 4. Adjusting rods 12 which are attached to the lugs 26 within the chambers 13, extend parallel to the axis of the casing 4 and through stuffing boxes 16 and guide brackets 17. The outer extremities of the adjusting rods 12 are connected with the swinging ends of pivotally supported adjusting arms 11 by means of links 18, as shown in Fig. 4, and the adjusting arms 11 are swingable by means of an adjusting shaft 10 associated with the turbine governor or other actuating means in a well known manner.

The nozzle specifically illustrated in Figs. 2, 3, 4 and 5, differs from that disclosed in Fig. 1 by having an additional guide comprising guide arms 19 and a guide bearing 20, associated with the needle 15 closely adjacent to the orifice ring 6. The needle 15 is likewise of torpedo shape but is somewhat longer than the needle 5 of Fig. 1. The actuating mechanism of the needle 15 is identical with that of Fig. 1 and the guide arms 11

19 are formed relatively thin measured transversely of the direction of flow in order to produce minimum obstruction. In order to permit the use of the guide arms 19 and guide bearing 20 as in Figs. 2, 3, 4 and 5, an additional casing section 21 may be utilized, this casing section 21 being detachably associated with the end of the main casing 4 and having the cap 8 detachably associated therewith as shown.

The modified form of nozzle illustrated in Fig. 6 differs from that disclosed in Fig. 1 by utilizing a special casing section 22 having the chambers 23 formed therein, for guiding and supporting the needle 25. This special casing section 22 may be detachably associated with the end of the main casing 4 and facilitates casting, machining, and removal of the nozzle elements. The needle 25 of the nozzle illustrated in Fig. 6 is likewise of torpedo shape and is adjustably sustained only by the supports 9 which are similar in construction to the needle supports of Fig. 1.

During operation of the turbine, the needle 5, 15, 25 is adjustable along the central axis of the rectilineal conduit formed by the casing 4, by manipulation of the adjusting shaft 10 and the adjusting arms 11. The needle is obviously moved in line with the nozzle orifice ring 6 at all times, and as the needle approaches the orifice, the diameter of the jet 7 is decreased. The limits of adjustment of the needle are such that the orifice may be entirely closed, or opened to produce a jet of maximum diameter. The adjustable supports 9 provide simple and effective means for guiding and supporting the needles with minimum obstruction to the flow. While the use of an additional supporting bearing 20 such as shown in Figs. 2, 3, 4 and 5 may produce slight additional obstruction to the flow, the guide arms 19 may also serve to prevent whirling in the flow directly in advance of the nozzle orifice, thereby producing a jet of maximum efficiency. It will be apparent that in each of the embodiments the use of bends in the conduit are avoided, the fluid being directed rectilineally toward the nozzle orifice and being prevented from whirling by the relatively thin needle supports 9. These supports however present minimum obstruction to the flow and may be readily manipulated from the exterior of the casing 4 by means of the lugs 26 and the rods 12 without additionally obstructing the flow. The flanges 14 further prevent disturbances in the flow and the stuffing boxes 16 prevent undesirable escape of water. The structure embodying the invention is moreover relatively compact and of extremely simple formation thereby enabling its manufacture at minimum cost.

It should be understood that it is not desired to limit the invention to the exact de-

tails of construction and operation herein shown and described for various modifications within the scope of the claims may occur to persons skilled in the art.

It is claimed and desired to secure by Letters Patent:

1. In a nozzle, a casing forming a conduit of uniform internal diameter having an end orifice of reduced cross-section, a needle located entirely within said conduit and movable relative to said orifice, a plurality of supports for said needle extending through said casing on opposite sides of said conduit, and mechanism associated with said supports beyond the opposite sides of said conduit for moving said supports and said needle. 70

2. In a nozzle, a casing forming a conduit of uniform internal diameter having an end orifice of reduced cross-section, a needle located entirely within said conduit and movable relative to said orifice, a plurality of supports for said needle extending through said casing on opposite sides of said conduit, and mechanism associated with said supports beyond the opposite sides of said conduit for moving said supports and said needle, said mechanism including a common shaft for simultaneously applying motion to several of said supports. 85

3. In a nozzle, a casing forming a conduit of uniform internal diameter having an end orifice and a plurality of side openings, a needle located entirely within said conduit and movable relative to said orifice, a plurality of supports for said needle extending through said openings on opposite sides of said conduit, mechanism associated with said supports beyond the opposite sides of said conduit for moving said supports and said needle, and means for sealing said openings for all adjustments of said needle. 95

4. In a nozzle, a casing forming a conduit of uniform internal diameter having an end orifice and openings in the opposite sides thereof, a needle located entirely within said conduit and movable relative to said orifice, a plurality of supports for said needle extending through said openings on opposite sides of said conduit, mechanism associated with said supports beyond the opposite sides of said conduit for moving said supports and said needle, said mechanism including a common shaft for simultaneously applying motion to several of said supports, and means for sealing said openings for all adjustments of said needle. 110

5. In a nozzle, a casing forming a conduit of uniform internal diameter having an end orifice, a needle located entirely within said conduit and movable relative to said orifice, said needle having opposite pointed ends disposed coaxial with said orifice and said conduit and being surrounded by a relatively free annular space, a plurality of supports for said needle extending through said cas- 125

ing on opposite sides of said conduit, and mechanism associated with said supports beyond the opposite sides of said conduit for moving said supports and said needle.

5 6. In a nozzle, a casing forming a conduit of uniform internal diameter having an end orifice, a needle located entirely within said conduit and movable relative to said orifice, said needle having opposite pointed ends disposed coaxial with said orifice and said conduit and being surrounded by a relatively free annular space, a plurality of supports

for said needle extending through said casing on opposite sides of said conduit, and mechanism associated with said supports beyond the opposite sides of said conduit for moving said supports and said needle, said mechanism including a common shaft for simultaneously applying motion to several of said supports. 15 20

In testimony whereof, the signature of the inventor is affixed hereto.
